DESIGN FOR A CABINET FOR INTER-COMMUNICATING SYSTEMS

Russell D. Jameson, Clark County, near New Carlisle, Ohio

Application October 27, 1936, Serial No. 65,545

Term of patent 3½ years

To all whom it may concern:

Be it known that I, Russell D. Jameson, a citizen of the United States, residing in the county of Clark, near the town of New Carlisle, and State of Ohio, have invented a new, original, and ornamental Design for a Cabinet for Intercommunicating Systems, of which the following is a specification, reference being had to the accompanying drawing, forming part thereof.

The figure is a perspective view of a cabinet for intercommunicating systems, showing my new design.

The rear portion of the cabinet is plain and flat and the end portion not shown is of the same design as the end portion shown on the drawing.

I claim:

The ornamental design for a cabinet for intercommunicating systems, as shown and described.

RUSSELL D. JAMESON.
